UNITED STATES PATENT OFFICE.

LEWIS D. GIDDENS, OF WILSON, NORTH CAROLINA.

CLOCK.

1,104,043.

Specification of Letters Patent. Patented July 21, 1914.

Application filed September 8, 1913. Serial No. 788,664.

To all whom it may concern:

Be it known that I, LEWIS D. GIDDENS, a citizen of the United States, residing at Wilson, in the county of Wilson and State of 5 North Carolina, have invented certain new and useful Improvements in Clocks, of which the following is a specification.

My invention relates to improvements in 10 clocks, and has particular reference to a signal clock provided with an improved form of alarm mechanism therefor adapted to sound at the terminal of a certain period of time and automatically re-set itself to sound when said period has again elapsed, the invention 15 being further designed as an improvement upon the clock covered by Letters Patents No. 990,809 and dated April 25, 1911, and No. 1,061,741, dated May 13, 1913, granted to me, and to which for a full and 20 clear understanding of the general construction, advantages and operation of my improvements I invite attention.

The leading object of my invention is the 25 provision of a mechanism of the character described and for the purpose stated which will comprise few working parts to insure reliability of operation and little risk of the mechanism getting out of order and which will dispense entirely with springs for operating certain of the parts thereby preventing 30 breakage of parts of the mechanism.

Another object of my invention is the provision of an improved signal mechanism for 35 clocks, which mechanism is especially adapted for use in mills where cotton seed is boiled to extract the oil, my device providing an alarm mechanism which can be set to warn workmen at the termination of the period of time which the seed should remain in the vat 40 and thus permit said workmen to occupy themselves with other work instead of it being necessary for them to remain by the vat due to the lack of suitable alarm mechanism which will give warning at the termination 45 of a certain number of minutes.

The further object of my invention is the provision of an alarm mechanism which can be set to give a signal at the end of a desired number of minutes and which will be 50 automatically released after giving said signal and will re-set itself to repeat the alarm when said number of minutes have again elapsed.

To attain the desired objects, my invention 55 comprises a ratchet wheel secured on the

rear end of the shaft bearing the minute hand of the clock and rotating therewith, and a pawl adapted to be engaged by the ratchet wheel and carried around thereby, an abutment for engaging and releasing the 60 pawl, an electric current associated with the clock and containing an alarm actuated when the pawl engages the abutment, and means for preventing the alarm mechanism from being sounded when desired, the invention 65 further residing in the novel features of construction and combination and arrangement of parts for service, substantially as described and as illustrated in the accompanying drawings.

Figure 1 is a front elevation of the complete invention. Fig. 2 is a rear elevation of a clock equipped with my improvements and illustrating particularly the alarm mechanism. Fig. 3 is a vertical sectional view 75 taken on the line 2—2 of Fig. 2. Fig. 4 is a detail perspective view of the clamping collar for the index lever, and Fig. 5 is a detail view of the oscillating pawl and the weight used to hold the pawl in engagement with 80 the teeth of the ratchet wheel.

In the drawings, in which similar characters of reference are employed to designate corresponding parts in the several views, the numeral 1, denotes the clock having the face 85 2, provided with the customary designations for indicating the time and having the minute hand 3 mounted on the arbor or shaft 4, and the hour hand 5. The shaft 4, has the threaded reduced portion or extension 6, and around the shaft is placed the ring or collar 7, which is provided with recesses 7^a adapted to receive screws 8, which pass through suitable openings in the clock casing so as to secure the collar in place.

The numeral 9, designates an arm secured under the collar as best shown in Fig. 3, and formed with the pointer 10, projecting unto the face of the clock and having an abutment 11, for engaging the pawl or dog 27, 95 hereinafter described. A ratchet wheel 12, is secured upon the collar 13, mounted on the extension 6, which is provided with a screw nut 14, spaced between which and the ratchet wheel is the loosely mounted trip lever 15, formed with the vertical extension 16, terminating in the cam shaped abutment portion 17, and having a lateral extension 18, over which passes one end of the tripper rod 19, retained in place by the screw 20, the 100 105 110

other end of the tripper rod is secured by the screw 21, upon the arm 22, of the spider shaped frame 23, which is pivoted upon the shaft 23^a said shaft being secured to the back of the clock, the frame 23 is also provided with the arm 24, carrying the weight 24^a the frame is also provided with the lever 24^b which is bent at right angles and passes through the slot 1^a and has secured to the end thereof a knob 25.

Pivots secured to the extension 6, is the plate 26, and pivotally mounted upon this plate is the pawl 28, having a pin or stud 29 which is adapted to engage the teeth 15 of the ratchet wheel 12, the pawl is also provided with the extended arm 30, the purpose of which will be seen later. The plate 26, is also provided with the weight 31, which is pivoted at 32, said weight being disposed to bear against the extended arm 20 of the pawl 28. A pair of abutment pins 33, are also arranged in the plate so as to limit the movement of the pawl and weight. The plate 26, is further provided with the 25 projecting portion 34, to which is connected a wire 35, said wire passing through the binding screw 36, and being grounded in an alarm device 36' a battery 37, being connected with the alarm device and having a 30 wire 38, passing through the binding screw 39, and terminating in the contact plate 40, which is mounted in the clock.

The operation of my device will be readily understood by reference to Fig. 2, from 35 which it will be seen that the ratchet wheel rotates on movement of the minute hand, thus making one revolution an hour, if the ratchet wheel contains but 60 teeth, and that the pawl is adapted to engage one of the teeth 40 of the ratchet and thus carry the plate 26, around with the ratchet to contact with the contact abutment 40, of the clock, and thus establish a circuit to sound the alarm, the cam portion of the trip lever engaging the 45 pawl just above the ratchet and the continued movement of the ratchet causing the pawl to ride upward on said shaped cam abutment until it is free of the ratchet, when the pin or stud is released from the ratchet the 50 spring 41, secured at one end to the clock casing and the other end being secured to the extended arm 42, of the plate 26, will swing the plate back and down from the cam abutment 17, and the contact point 40, thus breaking the circuit and cutting off the 55 alarm, the trip lever being retained against improper movement by means of the abutment 44, carried by the clock, the abutment 11, of the arm 9, limiting the movement of 60 the plate 26, in its downward course. When the coil spring 41, exerts its tension to return the plate 26, the pawl will be wedged between the abutment 11 and the wheel 12, and thus the stud 29, will be forced into engagement with the ratchet wheel 12, the po-

sition of the movable arm with respect to the contact 40, controlling the time between the arms.

It will thus be seen that I provide a simple, inexpensive and durable device which may be readily applied to an ordinary clock by securing an extension on the minute hand arbor and which will be of the highest efficiency and will positively operate at the terminal of each period of time without necessitating the re-setting of the device, and which is particularly adapted for use in schools to denote the time to change classes, in shops where certain work requires attention only at stated intervals, permitting the workmen to be employed on other work between said intervals and be notified of the time to attend to their other work, or in kitchens to notify the cook when the desired number of minutes have elapsed for the cooking of certain articles, or my clock can be used in schools to sound the period of classes or recitations; in theaters to act as a call for the performers, and in fact, in any situation where a signal is desired at certain stated periods of time.

I claim:

1. The combination with the minute hand arbor of a clock, of a ratchet wheel mounted thereon to move therewith, a pawl bearing plate pivotally mounted on the arbor and carrying a pawl adapted to engage the ratchet, a trip lever mounted on the arbor and formed with an abutment adapted to engage and release the pawl, and an extension 95 formed on said trip lever, a trip rod connected at one end with said extension, and means consisting of a three-arm lever having a weight on one of its arms connected with said trip rod and operated exteriorly 100 of the clock for causing the trip lever to prevent the movement of the pivotal plate when desired.

2. The combination with the minute hand arbor of a clock, of a ratchet wheel mounted 110 thereon to move therewith, a pawl bearing plate pivotally mounted on the arbor and carrying a pawl adapted to engage the ratchet, a trip lever mounted on the arbor and formed with an abutment adapted to engage 115 and release the pawl, an electric current associated with the clock mechanism, one leg of the circuit terminating at a contact point carried by the clock and the other leg terminating at the pivotal plate, an alarm mechanism arranged on said circuit and actuated by the engagement of the plate with the contact point, a trip rod connected at one end of the trip lever and a three-arm lever carrying a weight to return the trip rod 120 and mechanism to normal position.

3. The combination with the minute hand arbor of a clock, of a ratchet wheel mounted thereon, a setting mechanism, a plate adapted to engage and be limited in its move- 130

ment in one direction by the setting mechanism, a pivoted pawl carried by said plate, a weighted arm, engaging said pawl, a trip mechanism adapted to be engaged by said pawl, an electric circuit associated with the clock mechanism and closed by contact of said pawl with a stationary contact, a stationary contact, an alarm in said circuit, and means consisting of a three-arm lever

carrying a weight and having one arm connected with the trip mechanism for returning the parts to normal position.

In testimony whereof I affix my signature in presence of two witnesses.

LEWIS D. GIDDENS.
